HARRY F. DUBBEN AND FRANK B. EASTON, OF NEW YORK, N. Y.

MUFFLER.

1,388,554.

Specification of Letters Patent. Patented Aug. 23, 1921.

Application filed March 17, 1920. Serial No. 366,480.

To all whom it may concern:

Be it known that we, HARRY F. DUBBEN and FRANK B. EASTON, citizens of the United States, and residents of New York, in the county of New York and State of New York, have invented certain new and useful Improvements in Mufflers, of which the following is a specification.

Our invention relates to an improved muffler; particularly a muffler for treating the exhaust gases of the engines of automobiles, aeroplanes, trucks and other motor vehicles.

An object of our invention is to provide a muffler which is of simple construction and inexpensive to manufacture, and which is adapted both to deaden the sound of the escaping gases and to eliminate practically all of the back pressure created in the cylinders of the engine by the action of such gases.

A further object of our invention is to provide a muffler by which the exhaust gases of an engine can be expanded and allowed to escape freely and noiselessly into the atmosphere, without substantially changing the direction of flow given to them in the exhaust pipe which conducts them away from the engine.

Another object of our invention is to provide a muffler which is adapted to permit part of the exhaust gases of an engine to escape into the atmosphere directly from the discharge end of the exhaust pipe and the remainder from an outlet which is supplementary to the discharge end of the exhaust pipe.

The above and other objects and advantages of our invention are clearly set forth in the following description, taken in connection with the accompanying drawings. This disclosure, however, is to be construed as explanatory only, and embodiments of our invention other than that actually shown herein may be made to the full extent of the general meanings of the terms in which the claims appended hereto, and defining our invention, are expressed.

In the drawings:

Figure 1 is a side view principally in longitudinal section of a muffler constructed according to our invention;

Fig. 2 is a sectional view on the line 2—2 of Fig. 1; and

Fig. 3 is a sectional view on the line 3—3 of Fig. 1.

The same numerals will identify the same parts throughout.

In the particular description of the drawings, we show at 1 a portion of the exhaust pipe of an internal combustion engine, this pipe leading from the outlets of the cylinders of the engine, and having a down-turned end 2, terminating in a discharge outlet 3. Just in advance of the down-turned portion 2, the exhaust pipe 1 bears a muffler casing or sleeve 4 mounted upon and surrounding the same, and being provided with an outlet nozzle 5, leading through the bottom of the casing 4 at one end in proximity to the down-turned end 2 of the pipe 1. The casing 4 is entirely closed except for the outlet nozzle 5, and it is of larger diameter than the pipe 1, so as to inclose a chamber which surrounds the discharge pipe and the interior of the discharge pipe 1 can communicate with this chamber through a number of openings or apertures 6.

In operation the exhaust gases flowing from the engine are expanded when they reach the casing 4, and enabled to escape into the atmosphere, partly through the outlet 3 at the discharge end of the pipe 1, and partly through the nozzle 5, leading from the casing 4. Some of the gases flow through the openings 6 into the casing 4, and then reach the atmosphere by way of the nozzle 5, and the remainder of the exhaust gases pass into the atmosphere by way of the exhaust pipe direct, partly by way of the outlet 3, and partly by way of some additional openings 7, which are located in the bend of the pipe at 2. The effect of the openings 6 is to enable the gases to expand as soon as they reach the casing 4, and the portion which flows into the casing 4 will be very little above the pressure of the atmosphere when the nozzle 5 is reached, and the remainder of the gases will be similarly reduced in pressure by the time they reach the openings 7 and the outlet 3. We may provide deflectors 8 on the inside of the bent portion 2 of the pipe 1, adjacent each of the openings 7, to insure that a certain portion of the exhaust gases will be directed outward into the atmosphere through the openings before the outlet 3 is reached.

The muffler can of course be mounted in any convenient position forward of the discharge end of the exhaust pipe 1, and can be secured to the pipe 1 in any suitable way. The number and size of the holes 6 will of course be varied according to circumstances, and the particular type of the engine with

which the pipe 1 is connected, and we may also make the holes round or square, or in the form of slits, or give them any other desirable shape. We have found in practice 5 that a muffler of this construction not only permits the exhaust gases to expand to such a degree that as they pass out into the air through the outlets 3, 5 and 7, the engine is rendered quite noiseless, but also causes the 10 entire disappearance of back pressure in the engine cylinders. With most mufflers the back pressure due to the exhaust causes a very appreciable loss of power, while with our muffler this loss of power, due to back 15 pressure created by the exhaust gases, is entirely avoided.

The muffler herein set forth can be made out of any convenient material, such as sheet metal and the baffle plates 8 can be provided 20 by cutting the pipe 1 in the bent portion 2, and then forcing the metal at the points where the cutting is effected inward. In this way both the openings and the deflectors 25 8 can be obtained by practically a single operation.

Having described our invention, what we believe to be new and desire to protect by Letters Patent of the United States is:

1. A muffler for exhaust gases comprising

an exhaust pipe having an outlet and a casing 30 surrounding said pipe, and pipe passing through the casing but communicating with the interior of same, said casing having an outlet for the exhaust gases adjacent the outlet of the pipe, whereby the gases pass from 35 the exhaust pipe through both said outlets without substantial change of direction, and back pressure due to said gases, is eliminated.

2. A muffler for exhaust gases, comprising 40 an exhaust pipe having an outlet, a casing surrounding said pipe, the pipe passing through the casing, and having openings to enable the pipe to communicate with the inside of the casing, said casing having an 45 outlet adjacent the outlet of the pipe, the exhaust pipe also having openings between the casing and its own outlet, and deflectors in the pipe adjacent each of said last mentioned openings, whereby back pressure due 50 to the exhaust gases, is eliminated and the gases escape through both said outlets without substantial change of direction.

Signed at New York, in the county of New York, and State of New York, this 6th 55 day of March, A. D. 1920.

HARRY F. DUBBEN.
FRANK B. EASTON.
